(57) **CLAIM**

The ornamental design for a domestic soda-water preparing device capsule, as shown and described.

DESCRIPTION

FIG. 1 shows a top, front, right side perspective view of the domestic soda-water preparing device capsule;
FIG. 2 shows a back elevational view thereof;
FIG. 3 shows a front elevational view thereof;
FIG. 4 shows a left side elevational view thereof;
FIG. 5 shows a right side elevational view thereof;
FIG. 6 shows a top plan view thereof; and,
FIG. 7 shows a bottom plan view thereof; and,
FIG. 8 shows a bottom, front, right side perspective view thereof.
The broken line portions are shown for environmental purposes and form no part of the claimed design.
